UNITED STATES PATENT OFFICE.

WELLINGTON F. HEADLEY, OF AKRON, OHIO.

PRINTING DEVICE.

1,088,778.

Specification of Letters Patent.

Patented Mar. 3, 1914.

Application filed October 19, 1911. Serial No. 655,578.

To all whom it may concern:

Be it known that I, WELLINGTON FRANCIS HEADLEY, a citizen of the United States, residing at Akron, in the county of Summit 5 and State of Ohio, have invented new and useful Improvements in Printing Devices, of which the following is a specification.

This invention relates to improvements in printing devices and has for its object the provision of means especially adapted to producing wavy lines on paper for furnishing a back-ground on which may be formed designs such as mottling or a moire effect although the invention is not limited to producing any particular formation of lines.

The invention contemplates the provision of means which will force the paper to be printed against an inked surface with varying degrees of intensity at different points 20 so as to produce heavy shadows or shaded portions tapering or becoming less intense with great accuracy and smoothness to produce beautiful even effects not heretofore capable of being produced. I accomplish 25 this result by means of a sheet of material constituting a base on which are mounted a plurality of projections of resilient material, usually rubber, having the base portions thereof larger than the projecting portions 30 or the apices so that the portions of the paper which are pressed forward by the apices or the projections will receive a greater supply of ink from the ink-plate than those portions which are pressed more 35 lightly by the sides of the projection which receive a constantly decreasing amount of ink so as to produce a shaded effect.

Further the invention contemplates the use of my improved device for pressing the 40 opposite side of a paper against the inked surface for producing the shaded effects as contradistinguished from inking the device itself and passing the same over the paper, so that at all times the device is free from 45 contact with ink.

With the foregoing and other objects in view, the invention consists in the novel construction, combination and arrangement of parts constituting the invention to be hereinafter specifically described and illustrated 50 in the accompanying drawings which form a part hereof wherein is shown the preferred embodiment of the invention, but it is to be understood that changes, variations and 55 modifications can be resorted to which come

within the scope of the claims hereunto appended.

In the drawings in which similar reference numerals indicate like parts in the different figures, Figure 1, is a sectional view 60 of a portion of a printing press showing my device in operative relation therewith; Fig. 2, is a perspective view of a small portion of my improved device; and, Fig. 3, is a small piece of printed matter showing the 65 results of the use of my improved device.

In the drawings the reference numeral 1 denotes an ordinary printing cylinder provided with a feed-table 2 and carrying dogs or catches 3 and having a guide 4 all of 70 ordinary construction. Below the cylinder 1 is a reciprocating member 5 a portion 6 of which constitutes an inked surface which can be inked through the medium of an ink roller 7. The portion 6 is a substantially 75 plain surface in contradistinction to a surface which may be formed by type or other parts adapted to themselves provide a design upon the sheet to be printed.

Mounted on the cylinder 1 and held in position by means of the dogs or catches 3 is a sheet 8 of suitable material usually metal, on which are secured by cement or otherwise, a plurality of projecting members 9 shown in the drawings as parallel strips, 85 segment-shaped in cross-section, and preferably formed of some resilient material such as rubber. The configuration of the strips 9 is immaterial but said strips should be provided with enlarged base-portions 90 where they are fastened to the plate 8 and should gradually taper toward their outer portions which engage the paper.

In use, the paper 10 is fed over the table 2 and is pressed against the ink surface 6 95 by means of the members 9, the degree of pressure being regulated as is usual in the printing art and the result is that there is produced on the paper an impression or marks corresponding in contour to the con- 100 form of the strips 9 and consisting of deep central portions 11 from which the color gradually shades off to the points 12 and usually at points midway between the marks 11 there is little or no color applied 105 to the paper.

It will be apparent that the representation of color as shown in Fig. 3 is only approximate, due to the limitations in the use 110 of the ink employed in the drawing but the

printed lines shade from the deepest point 11 to the points 12 in gradually decreasing intensity of color.

As will be understood, the surface 6, being substantially plain and therefore having a comparatively thin ink coating, will, when the sheet is forced in contact therewith by the strips 9, not place a solid color on the sheet throughout its face, but the varying degrees of pressure will cause a greater or less amount of ink to be taken up by the sheet, thus giving it the appearance shown in Fig. 3. Obviously, this imprinting on the face of the sheet is not of a particular design provided by the inked surface, the only design effect that it has being provided by the blanket device and due practically to the variations in pressure which are provided when the cylinder carries the sheet over the inked surface.

In use it is customary to make first of all a light impression by passing the paper through the printing press and drying the same after which the paper is again subjected to the press and the color deepened and rendered more uniform by the superimposition on the previous printed surface of a relatively thin transparent color or coating arranged to coat approximately the entire surface with the result that the lines or impression originally placed on the paper by the first impression will appear deepened or having greater intensity of color than the other portions which are less intensely printed, and the whole blended and covered by the superimposed transparent coating, so that there will be imparted to the finished article a wavy or moire effect with the entire surface completely covered, excepting where breaks or openings are intentionally left for altering the design.

It will, of course, be obvious that the degree or intensity of color of the first or line impression as well as the second or transparent impression may be varied within

wide limits, due to the degree of pressure employed and the design imparted to the originally printed sheet.

I claim:

1. In apparatus for printing sheets with a design varying in intensity, means for applying a primary design to the sheet, said means including a plain, unyielding inking surface uniformly inked, and an impression member for applying varying degrees of pressure to the sheet while the latter is in contact with said surface.

2. In printing apparatus, a design-forming impression element, a plain unyielding inking surface uniformly inked, and means for carrying the sheet to be printed between said element and surface.

3. In printing apparatus and in combination, a plain unyielding inking surface uniformly inked, a sheet carrier adapted to bring the sheet to be printed into juxtaposition with said surface, and means carried by the sheet carrier for bringing the sheet into facial contact with said surface with varying degrees of pressure.

4. In printing apparatus and in combination, a plain unyielding inking surface uniformly inked, a sheet carrier adapted to bring the sheet to be printed into juxtaposition with said surface, and means carried by the sheet carrier for bringing the sheet into facial contact with said surface with varying degrees of pressure, said means comprising an element carrying raised independent projections wider at their base than at the top, whereby varying degrees of intensity in the print may be provided.

In testimony whereof I have hereunto set my hand in presence of two subscribing witnesses.

WELLINGTON F. HEADLEY.
